ROTARY CUTTER

Frank P. Miller, Meadville, Pa., assignor to Mc-
Crosky Tool Corporation, Meadville, Pa., a cor-
poration of Pennsylvania

Application September 16, 1930
Serial No. 482,327

11 Claims. (Cl. 77—75.5)

This invention relates to rotary cutters of the type in which inserted blades are employed.

Briefly stated, the invention will be found to look to the provision of an inserted blade rotary cutter of increased strength and decreased cost of manufacture as compared with other rotary cutters intended for the same purpose, these results being attained through the elimination of such separately made blade clamping devices as screws, wedges and locking pins without, of course, a corresponding omission of function, it being noted that no cutting away and consequent weakening of the material forming the head of the rotary cutter is necessary for the accommodation of the blade clamping means embodied in this invention as is the case when screws, wedges, pins and the like are employed.

Another attribute of the invention resides in the means by which the blade may be adjusted to compensate for wear.

Other objects and advantages will be apparent during the course of the following description.

In the accompanying drawing forming a part of this application and in which like numerals are employed to designate like parts throughout the same,

Figure 1 is a fragmentary side elevation illustrating a preferred form of cutter, parts being broken away,

Figure 2 is an end elevation of the cutter head with one blade and the contiguous portion of the cutter head shown in section,

Figure 3 is a vertical transverse sectional view taken on line 3—3 of Figure 1,

Figure 4 is an end elevation of the cutter head and several of the blades in place, the view illustrating that the blades are held securely in place by rolling or peening the adjacent portions of the material forming the head into engagement with the blades,

Figure 5 is a perspective of a blade embodied in the invention,

Figure 6 is an end elevation illustrating a modification of the invention,

Figure 7 is an end elevation illustrating a further modification of the invention,

Figure 8 is an end elevation illustrating another expression of the invention.

In the drawing wherein for the purpose of illustration are shown several preferred embodiments of the invention, the numeral 10 designates a shank terminating in a diametrically enlarged head 12. The head 12 is shown in Figure 1 to be provided with an annular series of spaced parallel longitudinally extending slots 14, the bot-

tom walls of which extend approximately parallel to the periphery of the head and at an angle to the axis of the head so that by the forward adjustment of the blades 16 positioned in the slots the cutting diameter of the tool is increased.

Figures 2, 4 and 5 illustrate that each blade 16 is abruptly decreased in cross sectional area at a point between the inner and outer longitudinal edges thereof to define a lengthwise extending ledge or shoulder 20 preferably on the front or leading side wall thereof. As shown in Figure 4, the side walls of each blade receiving slot 14 are initially straight and are substantially parallel to each other and the ledges 20 are located within the slots so that when the contiguous portions of the material forming the head, 12 are peened or rolled into firm pressure and binding engagement with the ledges 20 for the full length thereof, the blades will be held securely in place against radial and endwise shifting.

By rolling or peening the portions of the head 12 contiguous to the ledges 20 into overhanging and pressure engagement with the ledges for the full length thereof retaining flanges 22 are formed and as shown in Figures 1 and 3 the rear portions of such flanges extend across the chamfered rear corners 24 of the blades to hold the blades against rearward movement in the slots thereof.

The rolling or peening of the peripheral portions of the head 12 into firm binding engagement with the ledges 20 of the blades forces the blades into firm seating engagement with the bottom walls of the slots. To provide for adjustment of the blades from time to time to compensate for wear and to restore the original cutting diameter of the tool, it is merely necessary to drive the blades forwardly and then roll or peen additional portions of the head into engagement with the chamfered rear ends of the blades. With the blades thus advanced and secured in place, the same may be reground in the usual manner.

Figure 1 and more particularly the blade shown in the lower portion of this figure illustrates that the ledge 20 extends at an angle to the inner edge of the blade so that when the blade is driven forwardly for adjustment purposes, the metal forming the associated retaining flange 22 is crowded and hence is caused to more firmly hold the blade in place. Of course, the material forming the head 12 is sufficiently ductile to allow the same to be worked without chipping while, on the other hand, the blades are made of a hard cutting metal.

The employment of the particular blade fastening means disclosed takes the place of the more

expensive separately made screws, wedges, fastening pins and the like employed in other cutters intended for the same purpose so that reduced cost of manufacture is attained. Also, the particular blade holding means embodied in this invention do not require the cutting away of substantial portions of the cutter head 12 to provide for their accommodation and in this manner an increase in the unbroken cross sectional area of the cutter head is accomplished with a consequent increase in the strength of the reamer or other rotary cutter in which the invention is embodied.

In further adverting to the increased cross sectional area of the head 12, attention is invited to Figure 3 in which it is illustrated that the rear lower longitudinal corner of each blade is cut away or is bevelled to meet or nearly meet the opposite longitudinal corner of the blade and the place of such material is taken by the material forming the head 12. Of course, this portion of each blade is not called upon to bear a substantial portion of the thrust incident to the operation of the tool and hence the blade is in no way weakened. On the other hand, the head 12 is strengthened by the addition thereto of metal made possible by the cutting away of the lower rear longitudinal corners of the blades.

The cutter head 12 may be decreased in external diameter toward the rear portion thereof to provide generous chip clearance and to maintain substantial parallelism between the periphery of the head and the ledge 20, thereby simplifying the peening or rolling operation.

In the form of invention illustrated in Figure 6, the body 30 of the rotary cutter is formed with a plurality of longitudinally extending slots 32 snugly receiving blades 34. The blades 34 are provided in the leading or forward sides thereof with shallow grooves 36, the inner walls of which constitute ledges into pressure engagement with which the contiguous portions of the head 30 are rolled, peened or otherwise forced to hold the blades firmly in place against shifting both radially and endwise. Of course, the rear portions of the flanges 38 defined by rolling or peening portions of the head 30 into engagement with the blades are engaged with the chamfered rear ends of the blades to further hold the blades against endwise shifting. The side walls of the slots 32 are shown to converge slightly, and the side walls of the blades also converge inward for flat contact with the side walls of the slots. In this case, the flanges 38 defined by rolling or peening portions of the head 30 urge the converging side walls of the blades into firm pressure engagement with the converging side walls of the slots and the inner edges of the blades need not engage the bottom walls of the slots.

In the form of invention illustrated in Figure 7, the head 40 is provided with an annular series of longitudinally extending slots 42 opening out through the periphery and forward ends thereof for the reception of blades 44, the side walls of the blades and the side walls of the slots being approximately parallel. The front or leading side of each blade is shown to be provided with a longitudinally extending groove 48 substantially semicircular in cross section and adapted for the reception of the contiguous peened portion of the material of the head so that the blade is held firmly in place against both radial and longitudinal shifting.

In that form of the invention illustrated in Figure 8, the head 50 is provided with an annular series of longitudinally extending slots 52 re-

ceiving blades 54 of a dissimilar metal. One side wall of each blade receiving slot 52 is shown to be rabbeted as indicated at 56 to provide for the reception of the longitudinally extending shoulders or ribs 58 of the opposed sides of the blades 54, the outer edge of the ribs defining ledges into engagement with which the contiguous portions of the material constituting the head 50 are rolled or peened with the result that the blades are held against axial and radial shifting. Of course, the rear ends of the blades are backed by the rear portions of the peened sections of the cutter head 50 and in this manner rearward movement of the blades under the strain of use is inhibited.

Like in the form of invention shown in Figures 1, 2, 3, 4 and 5, the blades shown in Figures 7 and 8 have the lower rear longitudinal corners thereof cut away or bevelled to meet or nearly meet the opposite lower longitudinal corners of the blades to the end that a greater unbroken cross sectional area of material forming the cutter head is allowed. Also, the cutter heads shown in the various forms of invention may taper toward the rear ends thereof to provide increased chip clearance in the direction of the rear end of the head and at the same time to maintain substantial parallelism between the periphery of the head and the ledges into which the adjacent portions of the head are peened, rolled or otherwise forced, this latter feature greatly simplifying the peening or rolling operation.

Having thus described the invention, what is claimed is:

1. In a rotary cutter, a head having a slot, a blade in said slot in advance of the rear end thereof and having a ledge on one side thereof, that portion of the head contiguous to the ledge being pressed into binding engagement with the ledge and into that portion of the slot rearward of the blade for pressure and restraining engagement with the rear end of the blade.

2. In a rotary cutter, a head having a slot, a blade forwardly adjustable in said slot and having a ledge on one side thereof, that portion of the head contiguous to the ledge being rolled into binding engagement with the ledge to hold the blade against shifting, the rolled portion of the cutter head being extended across a portion of the rear end of the blade to inhibit rearward shifting of the blade.

3. In a rotary cutter, a head having a slot diminished in depth toward the forward end thereof, a blade provided with a longitudinally extending ledge positioned within the slot, that portion of the head contiguous to said ledge being rolled into pressure engagement with the ledge and about the rear end of the blade to hold the blade against endwise and radial shifting, said ledge being extended at an angle to the inner edge of the blade, so that when the blade is moved forwardly during adjustment the rolled portion of the cutter head will be crowded and thereby caused to hold the blade more firmly in place.

4. In a rotary cutter, a head having an annular series of slots opening out through the periphery and forward end thereof, blades in said slots in advance of the rear ends thereof and abruptly decreased in cross sectional area at points between the inner and outer edges thereof to define ledges, portions of the material constituting said head being peened into pressure engagement with said ledges and into the rear portions of said

- slots for engagement with the rear ends of the blades to hold the blades in place.
5. In a rotary cutter, a head having an annular series of slots opening out through the periphery thereof, blades in said slots and abruptly decreased in cross sectional area at points between the inner and outer edges thereof to define ledges, portions of the material constituting said head being peened into pressure engagement with said ledges and the rear ends of the blades to hold the blades in place, the rear portions of the blades being chamfered for contact by the peened portions of the material constituting the head. 80
- 10 6. In a rotary cutter, a head having an annular series of slots opening out through the periphery thereof, blades in said slots and abruptly decreased in cross sectional area at points between the inner and outer edges thereof to define ledges, portions of the material constituting said head being peened into pressure engagement with said ledges and the rear end of the blades to hold the blades in place, the major portions of said ledges being extended at angles to the inner longitudinal edges of the blades. 85
- 15 7. In a rotary cutter, a head having a slot, a blade positioned in the slot and having one side wall thereof provided with a shallow groove extending out to the outer edge of the blade and defining a ledge, the portion of the material contiguous to said shallow groove being peened into said groove and into the slot at a point rearward of the blade for pressure and restraining contact with the rear end of the blade. 90
- 20 8. In a rotary cutter, a head having a slot opening out through the periphery thereof and having one side wall thereof rabbeted to define a recess, a blade in said slot and having one side thereof provided with a lengthwise extending rib received in the recess defined by the rabbeting of one side wall of the slot, the peripheral portion of said head contiguous to said rib being rolled into pressure engagement with said rib and into the slot at a point rearward of the blade for pressure and restraining contact with the rear end of the blade. 95
- 25 9. In a rotary cutter, a head having an annular series of longitudinally extending slots having side walls and transversely inclined bottom walls extended at acute angles to the side walls, blades in said slots and having the inner rear longitudinal edge portions thereof bevelled to form flat angularly disposed bearing surfaces resting on said transversely inclined bottom walls, portions of said head being pressed into overhanging and retaining engagement with the blades and across the rear ends of the blades to secure the blades in position. 100
- 30 10. In a rotary cutter, a head having a plurality of slots having bottom walls extended at an angle to the axis of the cutter, blades in said slots and having ledges between the inner and outer edges thereof, portions of said head contiguous to said ledges being forced into binding engagement with said ledges, said head being decreased in diameter toward the rear end thereof to provide chip clearances increased in the direction of the rear end of the head and to provide substantial parallelism between said ledges and the periphery of the head. 105
- 35 11. In a rotary cutter, a head provided with a plurality of slots opening out through the periphery thereof, blades adjustable longitudinally in said slots and provided with ledges, portions of said head contiguous to said ledges being forced into binding engagement with said ledges, said ledges being extended at acute angles to the inner edges of the blades so that the pressure contact between the ledges and the contiguous portions of the head will be increased coincident with longitudinal adjustment of the blades. 110
